[57] CLAIM

The ornamental design for a golf glove, as shown and described.

DESCRIPTION

FIG. 1 is a front perspective view of a golf glove showing my new design with the thumb in a closed position; FIG. 2 is a front perspective view thereof with the thumb in an open position;

FIG. 3 is a rear perspective view thereof;

FIG. 4 is a right side elevational view thereof; and

FIG. 5 is a left side elevational view thereof.

The characteristic feature of the design resides in the textured pattern on the front of the glove and on the rear flap in FIG. 3.

FIG. 2.

FIG. 1.

FIG. 5.

FIG. 4.

FIG. 3.
